UNITED STATES PATENT OFFICE.

CHARLES S. NOE, OF CHICAGO, AND JOHN KAUFMAN, OF FOX LAKE, ILLINOIS.

IGNITION DEVICE.

Application filed March 19, 1920. Serial No. 367,269.

To all whom it may concern:

Be it known that we, CHARLES S. NOE, a citizen of the United States, residing at Chicago, county of Cook, and State of Illinois, and JOHN KAUFMAN, a citizen of Switzerland, residing at Fox Lake, Ill., have invented new and useful Improvements in Ignition Devices, of which the following is a specification.

10 This invention relates to improvements in ignition devices or torches, and particularly to ignition devices for oil engines.

An object of the invention is to provide a device whereby oil at ordinary pressure is 15 supplied to a torch or burner through the action of compressed air or another compressed gaseous fluid, which is adapted to support the combustion.

It is also an object of the present invention 20 to provide a torch or ignition device wherein the compressed air exerts a suction effect upon the oil for supplying the same to the point of ignition, thereby making it unnecessary to exert a pressure upon the fuel to 25 be supplied.

Another object of the invention is to provide an ignition device or torch which draws the liquid fuel in the form of an even and thin film towards the point of ignition so as 30 to assure the complete combustion of this fuel, and it is also an object to provide means for regulating the thickness of the film or the amount of fuel supplied per time unit.

With these and other objects in view, an 35 embodiment of the invention is illustrated in the accompanying drawing to which reference is made in the following specification, and the novel features are pointed out in the appended claims.

40 In the drawing:

Fig. 1 is a diagrammatic side elevation of a combustion engine with the device applied thereto, and

Fig. 2 is a central longitudinal section 45 through the device itself.

The ignition device or torch is primarily designed for engines in which a surface portion, as, for instance, a ball has to be heated before the engine can be started. An engine of this character is shown in Fig. 1, wherein 1 indicates the frame of the combustion engine and 2 the surface of the ball which is to be heated by the torch. It may be noted, however, that the torch is not limited to this specific purpose, but can be applied wherever a flame of high temperature

with complete consumption of the fuel is desired. A bracket 3 mounted near the upper portion of the frame 1 serves for supporting the torch in proper relation to the 60 hot ball 2.

The torch, shown in detail in Fig. 2, consists of a head 4, having a tapped bore 5 at one end, which, in the interior of the head, is reduced to form a conical or tapering bore 6. 65 The tapped opening 5 serves for receiving a nozzle 7, which is provided on its outer surface with a suitable screw thread and which terminates in a tapering portion 8, corresponding in its angular dimensions to the tapering bore 6 of the head. This nozzle 7 has a central bore 9, which is reduced near the forward end of the conical portion 8, to a very small area representing a needle hole 10, and it serves for admitting compressed air into 70 the interior of the head 4. Owing to the threaded engagement of the nozzle with the bore of the head, the position of the nozzle may be adjusted longitudinally with respect to the bore, and for the purpose of maintaining the nozzle in adjusted position a nut 10' is mounted on the outer surface of the same, the nut being in engagement with the front surface of the head when it locks the nozzle 75 in place.

Another object of the invention is to provide an ignition device or torch which draws the liquid fuel in the form of an even and thin film towards the point of ignition so as 80 to assure the complete combustion of this fuel, and it is also an object to provide means for regulating the thickness of the film or the amount of fuel supplied per time unit.

With these and other objects in view, an 85 embodiment of the invention is illustrated in the accompanying drawing to which reference is made in the following specification, and the novel features are pointed out in the appended claims.

40 In the drawing:

Fig. 1 is a diagrammatic side elevation of a combustion engine with the device applied thereto, and

Fig. 2 is a central longitudinal section 45 through the device itself.

The ignition device or torch is primarily designed for engines in which a surface portion, as, for instance, a ball has to be heated before the engine can be started. An engine of this character is shown in Fig. 1, wherein 1 indicates the frame of the combustion engine and 2 the surface of the ball which is to be heated by the torch. It may be noted, however, that the torch is not limited to this specific purpose, but can be applied wherever a flame of high temperature

with complete consumption of the fuel is desired. A bracket 3 mounted near the upper portion of the frame 1 serves for supporting the torch in proper relation to the 60 hot ball 2.

The torch, shown in detail in Fig. 2, consists of a head 4, having a tapped bore 5 at one end, which, in the interior of the head, is reduced to form a conical or tapering bore 6. 65 The tapped opening 5 serves for receiving a nozzle 7, which is provided on its outer surface with a suitable screw thread and which terminates in a tapering portion 8, corresponding in its angular dimensions to the tapering bore 6 of the head. This nozzle 7 has a central bore 9, which is reduced near the forward end of the conical portion 8, to a very small area representing a needle hole 10, and it serves for admitting compressed air into 70 the interior of the head 4. Owing to the threaded engagement of the nozzle with the bore of the head, the position of the nozzle may be adjusted longitudinally with respect to the bore, and for the purpose of maintaining the nozzle in adjusted position a nut 10' is mounted on the outer surface of the same, the nut being in engagement with the front surface of the head when it locks the nozzle 75 in place.

Another object of the invention is to provide an ignition device or torch which draws the liquid fuel in the form of an even and thin film towards the point of ignition so as 80 to assure the complete combustion of this fuel, and it is also an object to provide means for regulating the thickness of the film or the amount of fuel supplied per time unit.

With these and other objects in view, an 85 embodiment of the invention is illustrated in the accompanying drawing to which reference is made in the following specification, and the novel features are pointed out in the appended claims.

40 In the drawing:

Fig. 1 is a diagrammatic side elevation of a combustion engine with the device applied thereto, and

Fig. 2 is a central longitudinal section 45 through the device itself.

The ignition device or torch is primarily designed for engines in which a surface portion, as, for instance, a ball has to be heated before the engine can be started. An engine of this character is shown in Fig. 1, wherein 1 indicates the frame of the combustion engine and 2 the surface of the ball which is to be heated by the torch. It may be noted, however, that the torch is not limited to this specific purpose, but can be applied wherever a flame of high temperature

with complete consumption of the fuel is desired. A bracket 3 mounted near the upper portion of the frame 1 serves for supporting the torch in proper relation to the 60 hot ball 2.

The torch, shown in detail in Fig. 2, consists of a head 4, having a tapped bore 5 at one end, which, in the interior of the head, is reduced to form a conical or tapering bore 6. 65 The tapped opening 5 serves for receiving a nozzle 7, which is provided on its outer surface with a suitable screw thread and which terminates in a tapering portion 8, corresponding in its angular dimensions to the tapering bore 6 of the head. This nozzle 7 has a central bore 9, which is reduced near the forward end of the conical portion 8, to a very small area representing a needle hole 10, and it serves for admitting compressed air into 70 the interior of the head 4. Owing to the threaded engagement of the nozzle with the bore of the head, the position of the nozzle may be adjusted longitudinally with respect to the bore, and for the purpose of maintaining the nozzle in adjusted position a nut 10' is mounted on the outer surface of the same, the nut being in engagement with the front surface of the head when it locks the nozzle 75 in place.

Another object of the invention is to provide an ignition device or torch which draws the liquid fuel in the form of an even and thin film towards the point of ignition so as 80 to assure the complete combustion of this fuel, and it is also an object to provide means for regulating the thickness of the film or the amount of fuel supplied per time unit.

With these and other objects in view, an 85 embodiment of the invention is illustrated in the accompanying drawing to which reference is made in the following specification, and the novel features are pointed out in the appended claims.

40 In the drawing:

Fig. 1 is a diagrammatic side elevation of a combustion engine with the device applied thereto, and

Fig. 2 is a central longitudinal section 45 through the device itself.

The ignition device or torch is primarily designed for engines in which a surface portion, as, for instance, a ball has to be heated before the engine can be started. An engine of this character is shown in Fig. 1, wherein 1 indicates the frame of the combustion engine and 2 the surface of the ball which is to be heated by the torch. It may be noted, however, that the torch is not limited to this specific purpose, but can be applied wherever a flame of high temperature

ing towards the opposite end to agree approximately with the smaller part of the opening 15 in the discharge nozzle 20. The two portions of the bore 19 are in alignment 5 and are preferably centrally disposed with respect to the ring 18.

The longitudinal adjustment of the discharge nozzle 20 with respect to the ring 18 is facilitated by providing said discharge 10 nozzle with a hexagonal head, which can be gripped by a socket wrench or similar tool. For the purpose of confining the flame issuing from the discharge nozzle 14, the head 4 is connected with a tubing 21, which may 15 be secured to the head by threaded engagement, as shown, and which is provided with a number of openings 22 in proximity to the forward end of the discharge nozzle for supplying additional air to the flame.

20 The operation of the nozzle will readily be understood from the above description and from a reference to Fig. 1, in which the receptacle 23 contains air or another combustion supporting gaseous fluid under pressure, this receptacle being connected by the pipes 24 with the nozzle 7. The oil flows from the receptacle 25 through the pipes 26 into the torch. The compressed air forcibly ejected through the needle hole 10 of the 25 nozzle 7 will exert a suction effect upon the surrounding space and will thereby propel the oil through the pipe 26 and through the bore 13 into the conical interspace between the nozzle and the head, in which space the oil is spread out in a thin film. In this condition the oil will be rapidly discharged through the narrow opening of the ring 18 and will at the same time be atomized, whereby the mixture of oil and air suitable 30 for perfect combustion is produced. This mixture can be ignited by a match or the like in the tubing 21 and it will then continue to burn at high temperature so as to heat the hot ball or other surface of the engine.

45 We claim:

1. In a device of the character described, the combination of a head, a nozzle for compressed air mounted in said head and longitudinally adjustable therein, said head having a tapering bore and the nozzle having a tapering portion entering said tapering bore in spaced relation thereto, an oil conduit 50 communicating with said tapering bore and with the interspace between said bore and said nozzle, the head being provided with another bore in alinement with the first named bore and terminating in a constricted port, and a discharge nozzle mounted in said other bore provided with a constricted opening in alinement with said port and air nozzle having a passage tapering in a direction opposite to that of the bore of the head.

60 2. In a device of the character described, 65 the combination of a head having a bore

with a tapering portion, a compressed fluid nozzle mounted in said bore and provided with a conical end corresponding to the tapering portion of the bore and adjustable so as to leave a narrow conical interspace 70 between the nozzle and the head, an oil conduit communicating with said narrow interspace, the head being provided with another bore in alinement with said first named bore and extending from the reduced end of said 75 tapering portion, a discharge nozzle mounted in said other bore, and a perforated ring interposed between said discharge nozzle and the head within said bore and affording an uninterrupted passageway between said 80 fluid and discharge nozzles.

3. In a device of the character described, the combination of a head having a cylindrical bore with a reduced conical portion, a compressed fluid nozzle adjustably mounted 85 in said bore and having a reduced end corresponding to the reduced portion of the bore, said end terminating in a relatively small aperture, an oil conduit communicating with the interspace between the nozzle and the reduced portion of the bore, a discharge nozzle mounted in alinement with said first named bore in the head and having a discharge passage tapering in opposite direction to the tapering portion of the first 95 named bore, a ring interposed between the discharge nozzle and said first named bore, said ring having a central passage composed of a cylindrical and a flaring portion and affording an uninterrupted passageway between 100 said nozzles, and means on the discharge nozzle for adjusting the same with respect to the ring.

4. In a device of the character described, the combination of a head having an axial 105 bore provided with a conical portion, a compressed air nozzle adjustably mounted in said bore and having a reduced end with a needle hole adapted for adjustable opposition to the tapering portion of the bore, an 110 oil conduit communicating with the interspace between said reduced portion of the bore and the reduced end of the nozzle, a bore extending from the opposite end of the head towards said first named bore and in 115 alinement therewith, a ring having a central passage in said second bore, the passage in said ring being cylindrical near the tapering portion of the first named bore and flaring outwardly from said tapering portion, a discharge nozzle adjustably mounted in said 120 second bore and having a discharge passage tapering in opposite direction and alining with the tapering portion of said ring opening, and a tubing secured to the head and surrounding the discharge nozzle, said tubing being provided with openings for supplying additional combustion air.

5. In an igniting device, a head having 125 a bore provided at its medial portion with 130

a tapered wall terminating in a discharge port, a recess beyond said port axially aligned with said bore, an air nozzle adjustably arranged in said bore and having a tapered 5 end lying proximate said tapered wall and a needle discharge opening in alignment with said port, a connection for oil to said bore, a discharge nozzle seated in said recess and having a flaring bore opposite to said tapered wall and a ring provided with an opening forming an uninterrupted passageway between said nozzles.

6. In combination, a head having an axial threaded bore extending from one end of 15 said head to substantially the medial portion thereof, said bore terminating at its inner end in a tapered portion affording a relatively small discharge port which communicates axially with a threaded recess extending from the other end of the head, a 20 nozzle for air only threaded into said bore and provided with a tapered discharge end coaxial with said discharge port and in adjustable relation with the tapered portion 25 of said bore to afford a conical passage, an outlet for oil only communicating with said conical passage, and a discharge jet or nozzle having a flaring mouth and a constricted opening in alignment with said discharge nozzle.

7. In combination, a head having an axial threaded bore extending from one end of said head to substantially the medial portion thereof, said bore terminating at its inner end in a tapered portion affording a relatively small discharge port which communicates axially with a threaded recess extending from the other end of the head, a nozzle for air only threaded into said bore 40 and provided with a tapered discharge end coaxial with said discharge port and in adjustable relation with the tapered portion of said bore to afford a conical passage, an outlet for oil only communicating with said 45 conical passage and a discharge jet or nozzle disposed in said threaded recess and hav-

ing a tapered bore with its smaller end adjacent to and coaxial with the discharge port.

8. In combination, a head having an axial 50 threaded bore extending from one end of said head to substantially the medial portion thereof, said bore terminating at its inner end in a tapered portion affording a relatively small discharge port which communicates axially with a threaded recess extending from the other end of the head, a nozzle for air only threaded into said bore and provided with a tapered discharge end coaxial with said discharge port and in adjustable relation with the tapered portion 55 of said bore to afford a conical passage, an outlet for oil only communicating with said conical passage, a discharge jet or nozzle disposed in said threaded recess and having a tapered bore in opposition to said tapered passage and coaxial therewith, and a washer having an axial opening therein and said washer being disposed between said air nozzle and discharge nozzle.

9. In an igniting device, a head having a tapering inner end wall terminating in a constricted port which communicates with an axial recess in the head, a connection for oil to said bore, an air nozzle longitudinally adjustable in said bore and having a tapering end arranged near said tapering wall for controlling the passage of oil through said port, a discharge nozzle in said recess and having a passageway tapering 80 opposite to tapering of the bore, and a washer between said discharge nozzle and air nozzle and having an axial constricted opening affording an uninterrupted passageway between the bore and discharge nozzle. 85

In testimony whereof, we have affixed our signatures in the presence of two witnesses.

CHARLES S. NOE.
JOHN KAUFMAN.
